PAPER STUFFING MACHINE

Joseph Hartmann, North Kansas City, and John G. Campbell, Kansas City, Mo., assignors of fifty-one per cent to William L. Suiter, Kansas City, Mo.

Application July 29, 1937, Serial No. 156,370

15 Claims. (Cl. 270—55)

This invention relates to improvements in a sheet material inserting machine and particularly to a paper stuffing machine suitable for assembling the folded sections of a newspaper, and has for its objects to provide a simple and compact machine capable of handling a relatively large number of papers and deliver them properly associated to a common point.

With these, and other objects which will appear during the course of the specification, in view, reference will now be had to the drawings, wherein:

Figure 1 is a plan view of a paper stuffing machine embodying this invention.

Fig. 2 is a side elevation of the machine shown in Fig. 1.

Fig. 3 is an enlarged, fragmentary, sectional view, taken on line III—III of Fig. 1.

Fig. 4 is an enlarged, vertical, sectional view, taken on line IV—IV of Fig. 1.

Fig. 5 is a detached elevation of a portion of the paper delivery mechanism.

Fig. 6 is a sectional plan view, showing the paper-receiving mechanism.

Fig. 7 is an enlarged, detailed view of one of the operating cams and associated parts.

Fig. 8 is a sectional view, taken on line VIII—VIII of Fig. 3.

Fig. 9 is a sectional view, taken on line IX—IX of Fig. 3.

Fig. 10 is a fragmentary view, showing one of the pockets with the suction cups in closed relation.

Fig. 11 is a view similar to that shown in Fig. 10, with the vacuum cups moved to the open position.

Fig. 12 is a view similar to Fig. 11, with two of the folded sections inserted into the outer section.

Fig. 13 is an enlarged, fragmentary, sectional view, showing the suction cup mechanism in two positions.

Fig. 14 is a sectional view, taken on line XIV—XIV of Fig. 13.

Fig. 15 is an enlarged, sectional view, taken on line XV—XV of Fig. 8.

Fig. 16 is an enlarged, sectional view, taken on line XVI—XVI of Fig. 9.

Fig. 17 is an enlarged, plan view, partly in section, of one of the units and the central operating cam.

Fig. 18 is an elevation of one of the pockets and associated parts, looking against the direction of travel.

Fig. 19 is an enlarged, end elevation of feed rollers, with their supporting members, and,

Fig. 20 is a fragmentary elevation of the means for removing the assembled folded sections from their respective pockets.

Throughout the several views like reference characters refer to similar parts, and the numeral 20 designates a central, hollow standard, carried by a flanged base 22 of sufficient extent to insure stability to the structure. Rigidly attached to the upper end of standard 20 is a frame 24, which serves to support a series of spaced-apart magazines 26 and 28, provided with individual, adjustable standards 30, by means of which the heavily loaded magazines are prevented from sagging.

The magazines are alike in construction and comprise an arcuate housing 32, open at its outer end for the reception of a stack of folded sections 34 of a newspaper, etc. The inner end of said magazine is partially closed at its upper side by means of wall 36 which serves as an abutment for the papers. A follow-up weight 38 serves to force the stack of papers against wall 36 as the inside papers are fed from the magazine, as hereinafter set forth. A spring-actuated follow-up plate might be used instead of the gravity weight when the stack is so positioned as to preclude possible fall of the weight.

The individual folded sections are successively fed from the stack by means of the following mechanism, best shown in Figs. 3, 13, 14 and 17. A tubular arm 40, slidably mounted in the T-shaped sleeve 42, which in turn is securely mounted on rocker arm 44, pivotally carried by brackets 46, is adapted to carry at its outer end a suction cup 48, made of pliable material, such as rubber. Brackets 46 are rigidly carried by bars 50 secured to arms 51 of frame 24, and are positioned in spaced-apart relation relative to the magazine 26. To facilitate proper movement of the folded sections 34 from the magazine, two of the suction cups 48 with associated parts are provided to engage the paper at different points. A spring 52, positioned on arm 40 intermediate sleeve 42 and an adjustable collar 54, serves to maintain the suction cup 48 against the outer folded section 34 of the stack, except when otherwise retracted, as hereinafter described.

A fitting 56 carried by arm 40 serves to interconnect the outer ends 58 of the bifurcated tube 59 with said hollow arm 40, which in turn communicates with the vacuum cup 48 through opening 60. An arm 62 is secured to rocker arm 44 and connects with push arm 64, which is op-

erable by a rotatably mounted cam 66 to move said rocker arm in one direction against the action of spring 68, which normally holds the arm 40 in a substantially horizontal position. 5 The push rod 64 is slidably mounted in bracket 70 mounted on cross bar 72 carried by arms 50. The compression spring 68 is positioned under tension between bracket 70 and the adjustable collar 74 so as to produce a lifting effect 10 on the suction cups. The inner portion of push arm 64 is slidably mounted in a bracket 76 carried by frame 24. Roller 78, secured by the bifurcated fitting 80 to the end of arm 64, serves to eliminate much of the friction with the cam. 15 It has been found necessary to raise the suction cups from the surface of the stack of folded sections 34 during their upward stroke, and for this purpose the following mechanism is provided. Spaced-apart brackets 82, mounted on cross bar 84, carried by arms 50, are adapted 20 to encompass respectively the tubular arms 40. Each of the inner walls of the bifurcated bracket 84 is provided with a pivoted cam 86, between which the arm 40 moves in its oscillatory movement. The cam 86 is normally held with its 25 lower end portion in an outward position by means of spring 88 engaging pin 90 carried by cam 86. The oscillation of the cam is limited in two directions by the pin 90 which passes through arcuate slot 92 formed through the wall of bracket 82. 30 Pins or rollers 94, carried at opposite sides of arm 40, ride along the outer face 96 of cam 86, thereby causing the cam to rotate against the action of spring 88 until such time that the roller leaves the cam when the cam, through the action of spring 88, will move forward so that the pins 90 will move along the inner face 96 and force the vacuum cup 48 away from the stack against the action of spring 52. When the arm 40 has again been moved to its raised position by the action of spring 68, then spring 52 will cause the suction cup to be again forced against the stack of paper. 40 At each downward stroke of the suction cup 48, a folded section 34 is fed downwardly between two sets 98 and 100 of revolving feed discs 102, mounted on shafts 99 and 101 respectively, which force the folded sections downwardly to receiving members hereinafter described. The inner 50 set of discs 100, carried by brackets 104, are driven by means of an individual motor 106 which may directly connect thereto. The outer set of discs 98 are mounted for rotary movement in brackets 110 and are urged against the discs of set 100 by means of compression springs 112. A driving means common to all the feed mechanisms might be used instead of the individual drive units. 55 Referring now to the rotary parts mounted on standard 20, reference will be had to Fig. 3. Rigidly secured adjacent base 22, to standard 20, is a ball race 114, provided with balls 116. A drive pulley 118 is rotatably mounted on standard 20 60 and has a ball race 119 which serves to receive balls 116. A motor 120, carried by frame 122, is interconnected with drive pulley 118 by belt 124, whereby the same is rotated on standard 20. A carrying frame 126, having a hub 128 keyed to 65 the hub of pulley 118, is provided with radial arms 130, each bifurcated at its outer end to receive and support paper receiving pockets 132 and 134. 70 Sleeve 136 is secured at its lower end in concentric relation with standard 20, and is provided

at its upper end with a rigidly attached cam 66 which rotates therewith about the standard. A valve assembly 138 is provided and adapted to be fitted on sleeve 136 adjacent cam 66 to control the vacuum to the suction cups 48. The details of valve 138 are best shown in Figs. 3, 8 and 15, and consist of a stationary jacket 140, held against rotation by any suitable means such as the vacuum pipes 142 and 144, a cover plate 146, and an inner valve member 148, secured for rotation with sleeve 136. Member 148 is so formed and positioned in jacket 140 as to produce a vacuum chamber and to present a series of equally spaced valves 152, whereby the ports 154 formed in jacket 140, with which the respective vacuum tubes 59 communicate, are caused to be closed. Recesses 156 formed in the face of valves 152, communicate with ports 158 in the under side of cover plate 146 to allow the inrush of air when it is desired to release the hold of the suction cup on the paper section. It will be observed that by the use of this valve assembly 138, an opening and closing of each port 154 seven times during each revolution of sleeve 136 is obtained, thereby making it possible to deliver to each of the seven pockets 132, one folded section 34 from each of the outer magazines 26, thus delivering three of the folded paper sections to each pocket in a fixed relation, as hereinafter described. 30

The inner magazines 28 have like parts, as just described, and folded paper sections are delivered therefrom to the inner series of receiving pockets 134 in like manner.

All of the paper receiving pockets 132 and 134 in both the inner and outer series are substantially the same, so that but one will be described. The pocket proper consists of a U-shaped member 160, secured to arm 130 by angles 162. These pockets are equally spaced circumferentially and are adapted to pass beneath their respective paper delivery mechanism at such time as the paper sections 34 are being delivered therefrom, so that they will be properly deposited. At the rear end of each pocket, determined by the direction of travel as indicated by arrows, is a very flexible spring 164, which serves to prevent accidental end movement of the papers delivered to the pocket, but will flex and permit the removal of the paper assembly from the pocket as herein-after described. 45

Referring to Figs. 10, 11 and 12, which show the relative relation of the various folded sections of paper, it will be noted that the first folded section 34 deposited in the pocket is engaged by suction cups 166 and 168, as shown in Fig. 10, and then moved to the open position, as shown in Fig. 11, so that the folded sections 34A and 34B may be inserted and permitted to take the position shown, due to gravity and the centrifugal force caused by the rotary movement of the pocket. The vacuum cup 166 is carried by a fixed, hollow arm 170 carried by frame 126, and is in communication with a vacuum chamber 172, formed in valve assembly 174 (see Fig. 9) through a pipe 176. The inner suction cup 168 is carried by a hollow arm 178, pivoted at 180, and having a depending operating arm 182 which cooperates with the stationary cam member 184 once during each revolution of the pocket, about standard 20, 60 to cause the suction cup to take the forward position shown in Fig. 10, thereby opening the first folded paper section, delivered to the pocket, for the reception of the succeeding folded sections to be delivered therein. 70

5 The cam 184 carried by frame 122 serves to operate the suction cup for the outer series of pockets 132, while cam 186, carried by bracket 188, operates those of pockets 134. The arm 182 is normally held in the open position by means of the leaf spring 190, which is secured to frame 126.

10 The hollow arm 178 communicates with vacuum chamber 172 through flexible tube 192 and pipe 176, as clearly shown in Fig. 3. It is to be noted that all the suction cups herein referred to are saucer shaped and are in direct communication with a vacuum chamber, so that a definite suction may be created when the cup is closed by a sheet of paper.

15 Reference will now be had to valve assembly 174, wherein a rotatable housing 194 cooperates with a stationary core 196 to form a vacuum chamber 172. (See Figs. 3, 9 and 16.) A valve section 198, integral with core 196, is so positioned and constructed as to break the vacuum to each set of pockets once during each revolution. Each port 200 is first cut off by valve 198 and then placed in connection with the outside atmosphere through recess 202 formed in the outer face of valve 198 and the respective opening 204 formed in housing 194. This release of the vacuum is necessary to permit the removal of the assembled paper sections from the machine as hereinafter set forth. It will be noted that a portion of the pocket is cut away as at 206 to allow free movement of arm 178.

20 The entire suction system just described is provided with the required vacuum by pipe 145, which extends down through standard 20 and to any suitable means for creating a vacuum, not shown.

25 Referring now to the means for removing the assembled sections of folded paper from the machine, reference will be had to Figs. 1, 2, 4, 19 and 20, wherein the standards 208, secured together by means of tie rods 210, are adapted to support mechanism above the path of travel of pockets 132 and 134, which is operable to successively engage the assembled papers in the separate pockets and deliver them to a conveyor belt 212 for delivery to any desired location. Conveyor belts 212 pass over rollers 214, mounted on shaft 215, and are carried by the standards 208. The movement of belts 212 is in the direction shown by the arrows, and the driving means is herein-after described.

30 Reference will first be had to the specific means for removing the assembled sections A from the inner pocket. The pocket 134, in its rotary movement about standard 20, carries the assemblage A between the converging, collecting members 216, whereby the spaced-apart portions of the outer section of folded paper are drawn together and delivered between feed rollers 218 and 220. As soon as the upper edge of A is positioned between said rollers, roller 218, which is normally in the inoperative position, is moved toward roller 220 to securely engage the paper A and cause it to be ejected from the pocket. Roller 218 is mounted on shaft 219 for rotation in a carriage 222, which is adapted to be supported on wheels 224, and to be moved transversely by means of the push arm 226 having roller 228 at its inner end to engage the cam 230, which is similar to and integral with cam 66.

35 Cam 230 is provided with seven equally spaced undulations 232, whereby the rollers are caused to operate and engage the assembled papers in each of the seven series of pockets as they move

in operative relation therewith. This cam 230 might be eliminated and the carriage moved by cam 66, since they are identical in shape. Carriage 222 is normally held in the inoperative position and retracted by the action of springs 234. 5 Roller 236, mounted on shaft 237 and carried by carriage 222, cooperates with roller 238 mounted on shaft 239, carried by standards 208, to remove the assembled papers from the outer pockets 132. It will be noted that these rollers 218, 220, 236 and 238 are each made up of a series of spaced-apart roller elements, mounted on shafts for rotation therewith. A solid or circumferentially grooved roller might also be used.

10 The assembled folded sections marked A in Fig. 4, when delivered by the rollers 218 and 220, are directed by a short conveyor belt 240 to the conveyor belt 212. The belts 240 pass over rollers 220, then around discs 242, which are mounted for rotation with shaft 244 in standards 208. A shield 246 serves to maintain A in the proper path of travel. The rollers 236 and 238, mounted on shafts 237 and 239 respectively cooperate to feed the assembled folded sections B direct to the conveyor belt 212. Shield 248, carried by standards 208, prevents interference between belts 240 15 and the outgoing paper assembly B.

15 The assembled folded sections A and B, when gripped by the respective pairs of feed rollers, are resting against the spring 164, and due to the fact that the rotary motion of A and B is stopped, spring 164 will be deflected until the paper has been moved sufficiently high to free itself therefrom.

20 The motor 250 carried by standard 208 is provided with a pulley 252 which drives roller 220 through means of belt 254 and pulley 256, mounted on shaft 221, and also drives pulley 238 through belt 258 and pulley 260 mounted on shaft 239. The conveyor belt 212 is driven by a pulley 262, mounted on shaft 239, belt 264, and pulley 266 mounted on shaft 215. The relative speeds of the different parts driven by motor 250 may be changed by simply varying the size of the respective pulleys.

25 The assembled folded sections A and B are simultaneously engaged by their respective rollers, but B will reach the conveyor 212 ahead of A, since it has a shorter distance to travel. A variation in the rate of rotation of the respective feed rollers might be employed to space A and B 30 on the conveyor belt.

30 In the operation of this machine, the magazines 26 and 28 are filled with folded sections 34 and the follow-up weight 38 positioned to force the folded sections inwardly against suction cups 48. Motors 106 are energized to constantly drive roller 100, which in turn drives roller 98. Motor 250 is also provided with an electrical current to drive the ejector rolls and the conveyor belts, as described above. When said motors have attained their normal speed and the operating parts are in motion, then motor 120 is energized to rotate the pockets 132 and 134 with their associated parts, about the standard 20. Since the operation of each series of pockets 132 and 134 is substantially identical, it will be sufficient to describe the action of the series 132, which receive their folded sections from magazines 26.

35 In describing the relative positioning of the pockets and magazines, reference will be had to Fig. 1, and it will be noted that the pockets are considered to be rotating in the direction of the arrow. It will be considered that the pocket 132 directly beneath the ejecting means travels be- 40 45 50 55 60 65 70 75

neath the magazine 26, positioned at the left thereof, and receives a folded section 34. This first section deposited in pocket 132 is to be the cover section for subsequent folded sections deposited in said pocket, and is therefore engaged and moved to the open position by means of suction cups hereinbefore described in detail. This first section 34 is properly positioned in the open condition before said pocket reaches the succeeding magazine 26 in its forward travel.

When the pocket 132 is directly beneath the second magazine 26, another insert is deposited therein between the opened leaves of the folded section first deposited. This second deposited folded section is moved outwardly so as to rest against the outer leaf of the open section, due to centrifugal force. In like manner, the folded section from the third magazine 26 is deposited in pocket 132. These three assembled, folded sections are now ready to be ejected from the machine, and in due course move into operative relation with the ejecting mechanism and are delivered to the conveyor belts 212 and carried to any desired point. Each of the seven pockets 132 are likewise loaded and unloaded, thereby delivering at each revolution of the pockets, seven completely assembled, folded sections. The number of inserts may be increased or decreased by simply increasing or decreasing the number of pockets and associated magazines.

The series of pockets 134, which are concentrically arranged relatively to pockets 132, are adapted to receive folded sections from the inner magazines 28, and when in operation, will deliver a like number of assembled, folded sections as stated relative to pockets 132. It is very apparent that any desired number of series of pockets might be utilized in order to obtain the desired number of assembled, folded sections during a given period of time.

While the preferred form of operating means has been shown in the drawings, yet it is desired to be limited only by the scope of the appended claims.

What we claim is:

1. In a machine of the character described, a series of circumferentially disposed receiving pockets mounted for rotation about a common axis; spaced-apart stationary magazines, each adapted to support a stack of folded sections adjacent the path of travel of said pockets; means to deliver folded sections to said pockets from said magazines; and means to remove the assembled sections from the pockets.

2. In a machine of the character described, a series of pockets mounted for rotation about a common axis; spaced-apart stacks of folded sections supported on stationary magazines and adjacent the path of travel of said pockets; means operable to deliver a folded section from each of said stacks into each of said pockets during one revolution of the pockets; and means to remove the assembled sections from said pockets.

3. In a machine of the character described, a plurality of stationary magazines, each adapted to hold a stack of folded sections, a series of receiving pockets rotatably mounted and operable to successively pass adjacent each of said pockets; means operable to deliver a folded section from each of said magazines to each of said pockets at each revolution of the pockets; and means to remove the assembled sections from each pocket during said revolution.

4. In a machine of the character described, a series of circumferentially disposed receiving

pockets mounted for rotation about a common axis; spaced-apart magazines, each adapted to support a stack of folded sections adjacent the path of travel of said pockets; means timed with the rotation of said pockets to remove folded sections from said magazines and deliver them to said rotating pockets, whereby one folded section is delivered from each magazine to each pocket during a single revolution of said pockets; and means operable to remove the assembled folded sections from each pocket during each revolution of the pockets.

5. In a machine of the character described, a series of circumferentially disposed receiving pockets mounted for rotation about a common axis; spaced-apart magazines, each adapted to support a stack of folded sections adjacent the path of travel of said pockets; means timed with the rotation of said pockets to remove folded sections from said magazines and deliver them to said rotating pockets, whereby one folded section is delivered from each magazine to each pocket during a single revolution of said pockets; and means, timed with the rotation of said pockets, operable to remove the assembly of folded sections from each pocket during said single revolution of the pockets.

6. In a machine of the character described, a series of circumferentially disposed receiving pockets mounted for rotation about a common axis; spaced-apart magazines, each adapted to support a stack of folded sections adjacent the path of travel of said pockets; means to deliver folded sections to said pockets from said magazines; means to separate the leaves of the folded section first delivered to the respective pockets, whereby the folded section subsequently delivered will be positioned between said separated leaves; and means to remove said assembled folded sections from the pockets.

7. In a machine of the character described, a series of circumferentially disposed receiving pockets mounted for rotation about a common axis; spaced-apart magazines, each adapted to support a stack of folded sections adjacent the path of travel of said pockets; means to deliver folded sections to said pockets from said magazines; suction means to separate and secure the leaves of the folded section first delivered to the respective pockets in an open position, whereby subsequent folded sections deposited will be positioned between said separated leaves; and means to remove the assembled folded sections from the pockets.

8. In a machine of the character described, a series of circumferentially disposed receiving pockets mounted for rotation about a common axis; spaced-apart magazines, each adapted to support a stack of folded sections adjacent the path of travel of said pockets; means to deliver folded sections to said pockets from said magazines; suction means to separate and secure the leaves of the folded section first delivered to the respective pockets in an open position, whereby subsequent folded sections deposited will be positioned between said separated leaves; means to release the hold of the suction means on said first delivered folded section; and means to remove the assembled folded sections from the respective pockets when said suction means is inoperative.

9. In a machine of the character described, a series of circumferentially disposed receiving pockets mounted for rotation about a common axis; spaced-apart magazines, each adapted to

support a stack of folded sections adjacent the path of travel of said pockets; means to deliver folded sections to said pockets from said magazines; suction means to separate and secure the leaves of the folded section first delivered to the respective pockets in an open position, whereby subsequent folded sections deposited will be positioned between said separated leaves; means to release the hold of the suction means on said first delivered folded section; and means to remove the assembled folded sections from the respective pockets and deliver them on a conveyor belt, when said suction means is inoperative.

10. In a machine of the character described, a standard, a series of pockets mounted to rotate about said standard; spaced-apart magazines each adapted to support a stack of folded sections adjacent the path of travel of said pockets; oscillatable suction cups adapted to engage and deliver from the stack the inside folded sections during one direction of its movement and to be spaced apart from the stack during its movement in the other direction; feed rollers operable to receive and drive said folded section to one of said pockets as it moves adjacent thereto; means whereby the sheets of the first folded section delivered to each pocket are separated to receive the subsequently delivered folded section therebetween; and means to remove the assembled folded sections from the pockets during each revolution thereof.

11. In a machine of the character described, a standard, a series of pockets mounted to rotate about said standard; spaced-apart magazines each adapted to support a stack of folded sections adjacent the path of travel of said pockets; oscillatable suction cups adapted to engage and deliver from the stack the inside folded sections during one direction of its movement and to be spaced apart from the stack during its movement in the other direction; feed rollers operable to receive and drive said folded section to one of said pockets as it moves adjacent thereto; means whereby the sheets of the first folded section delivered to each pocket are separated to receive the subsequently delivered folded section therebetween; and means, including relatively movable, cooperating rollers, whereby the assembled folded sections in each pocket are engaged and ejected from said pockets during each revolution thereof.

12. In a machine of the character described, a series of circumferentially disposed receiving pockets mounted for rotation about a common axis; spaced-apart magazines, each adapted to

support a stack of folded sections adjacent the path of travel of said pockets; means to deliver folded sections to said pockets from said magazines; a stationary cam; and means, controlled by said cam, rotatable with said pockets, whereby the assembled folded sections delivered to each pocket are successively ejected therefrom.

13. In a machine of the character described, a plurality of series of circumferentially disposed receiving pockets mounted for rotation about a common standard; a series of spaced-apart magazines, adjacent the path of travel of each of said series of pockets, each adapted to carry a stack of folded sections; means associated with each magazine whereby a folded section is delivered to each pocket of its associated series during each revolution of the pockets; and means associated with each series of pockets whereby all assembled folded sections delivered thereto are ejected therefrom at each revolution of the pockets.

14. In a machine of the character described, a plurality of horizontally disposed, concentric series of circumferentially disposed receiving pockets mounted for rotation about a common standard; a series of spaced-apart magazines, adjacent the path of travel of each of said series of pockets, each adapted to carry a stack of folded sections; means associated with each magazine whereby a folded section is delivered to each pocket of its associated series during each revolution of the pockets; and means associated with each series of pockets whereby all assembled folded sections delivered thereto are ejected therefrom at each revolution of the pockets.

15. In a machine of the character described, a plurality of series of circumferentially disposed receiving pockets mounted for rotation about a common standard; a series of spaced-apart magazines, adjacent the path of travel of each of said series of pockets, each adapted to carry a stack of folded sections; means associated with each magazine whereby a folded section is delivered to each pocket of its associated series during each revolution of the pockets; means for separating the leaves of the initial folded section delivered to each pocket whereby folded sections subsequently delivered will be positioned between said separated leaves; and means associated with each series of pockets whereby all assembled folded sections delivered thereto are ejected therefrom at each revolution of the pockets.

JOSEPH HARTMANN.

JOHN G. CAMPBELL.
